UNITED STATES PATENT OFFICE.

A. WALDO ROCKWOOD, OF WINCHESTER, MASSACHUSETTS.

DESIGN FOR TRIMMING BRAID.

Application filed December 9, 1926. Serial No. 20,257. Term of patent 7 years.

To all whom it may concern:

Be it known that I, A. WALDO ROCKWOOD, a citizen of the United States, residing at Winchester, in the county of Middlesex and State of Massachusetts, have invented a new, original, and ornamental Design for Trimming Braid, of which the following is a specification, reference being had to the accompanying drawing, forming part thereof.

The figure is a plan view of trimming braid showing my new design.

I claim:

The ornamental design for trimming braid, as shown.

A. WALDO ROCKWOOD.
